(57) **CLAIM**

The ornamental design for a focus gear ring substantially as shown and described.

DESCRIPTION

FIG. 1 is a front, left, top perspective view of a focus rear ring;

FIG. 2 is a front view of the focus rear ring;

FIG. 3 is a rear view of the focus rear ring;

FIG. 4 is a left side view of the focus rear ring;

FIG. 5 is a right side view of the focus rear ring;

FIG. 6 is an enlarged view of a top view of the focus rear ring; and,

FIG. 7 is an enlarged view of a bottom view of the focus rear ring.

In the drawing, the focus rear ring is shown with symbolic breaks in its length depicted in broken lines. The appearance of any portion of the article between the broken lines forms no part of the claimed design.

1 Claim, 7 Drawing Sheets
